(57) **CLAIM**

The ornamental design for a corner shuffleboard table, as shown and described.

DESCRIPTION

FIG. 1 is a top and left side perspective view of a corner shuffleboard table showing my new design. Five game disks are shown in broken lines (three on the playing surface and two in a pocket at the right end of the table) and are not part of the design;

FIG. 2 is a top plan view thereof;

FIG. 3 is a bottom plan view thereof;

FIG. 4 is a front elevation view thereof;

FIG. 5 is a right side elevation view thereof; and,

FIG. 6 is a rear elevation view thereof.

FIGS. 2-6 are drawn in reduced scale.
